[57] CLAIM

The ornamental design for a double telephone jack frame, substantially as shown and described.

DESCRIPTION

FIG. 1 is a top plan view of the double telephone jack frame showing my new design, the bottom being a mirror image thereof.

FIG. 2 is a left end elevational view thereof.

FIG. 3 is a right end elevational view thereof.

FIG. 4 is a side elevational view thereof, the opposite side being a mirror image thereof.

FIG. 5 is a top, left end perspective view thereof, on a reduced scale.

FIG. 1

FIG. 2

FIG. 3

FIG. 4
